UNITED STATES PATENT OFFICE.

JOHN L. RIEGER, OF SANDUSKY, OHIO.

AWNIN*G*.

SPECIFICATION forming part of Letters Patent No. 272,772, dated February 20, 1883.

Application filed December 2, 1882. (No model.)

To all whom it may concern:

Be it known that I, JOHN L. RIEGER, a citizen of the United States, residing at Sandusky, in the county of Erie and State of Ohio, have invented certain new and useful Improvements in Awning*s*; and I do declare the following to be a full, clear, and exact description of the invention, such as will enable others skilled in the art to which it appertains to make and use 10 the same, reference being had to the accompanying drawings, and to letters or figures of reference marked thereon, which form a part of this specification.

Figure 1 of the drawings is a representation 15 of this invention in a perspective view. Fig. 2 is a perspective view of one form of the metallic loop. Fig. 3 is a perspective view, and shows the metallic loop and end loop in one piece.

20 This invention has relation to means for fastening awnings to the iron rods which are placed for the purpose over windows and doors; and it consists in the construction and novel arrangement of devices, as hereinafter set forth, 25 and particularly pointed out in the appended claims.

In the annexed drawings, the letter A designates an iron rod arranged over a door or window, and designed to afford a support to an 30 awning.

B represents the edge of an awning, and C the device whereby the awning is connected to the iron rod. The connection consists of a metallic loop having its outer end rounded to 35 fit the rod A, and made open on one side, as indicated at D, to enable it to be passed over the iron rod. This opening is therefore quite large, and in order to close it a spring-tongue, E, is attached to the end F of the loop-bar by 40 means of a pivot, G, which allows the tongue to be turned outward on either side to clear the opening D to its fullest extent. The spring therefore is not liable to be broken in putting

the loop on the rod. On the inside of the larger end of the loop-bar, at its extremity H, 45 is formed a recess, K, open at the end, and designed to receive the free end of the tongue E when the tongue is turned in the direction of the loop-bar to complete the loop. By means of this spring-tongue the loop is fastened on 50 the rod, so that it cannot become casually detached. The edge of the awning is fastened to a ring or end loop, L, which, for convenience and economy, is cast or formed entire with the loop C, at the smaller end thereof, the plane of 55 the end loop being at right angles to that of the main loop. The transverse bar of the end loop is made straight, so that when the edge of the awning is stitched thereto the tension on the awning where the threads have passed 60 through will be even and uniform, and they will not be liable to tear out. In some cases the loop C is made without the end loop and engages an awning-ring.

Having described this invention, what I 65 claim, and desire to secure by Letters Patent, is—

1. In an awning-support, the combination, with a supporting-rod, A, and the awning, of the metallic loop C, having the side opening, 70 D, end recess, K, and the spring-tongue E, pivoted to the loop-bar, so as to turn outward on either side to clear the opening to its fullest extent, substantially as specified.

2. The connecting-loop C for awnings, having the side opening, D, the side-turning spring-tongue E, the end recess, K, and the end loop, 75 L, extending at right angles to the main loop and formed with a straight cross-bar, substantially as specified.

In testimony whereof I affix my signature in presence of two witnesses.

JOHN L. RIEGER.
